THREE-PHASE A.C. ELECTRIC CIRCUIT-BREAKER
 Jan C. Clason and Geert C. Damstra, Hengelo, Netherlands, assignors to N.V. Fabriek Van Electrische Apparaten Voorheen F. Hazemeijer & Co., Hengelo, Netherlands, a corporation of the Netherlands

Filed June 23, 1960, Ser. No. 38,158

Claims priority, application Netherlands June 30, 1959
 5 Claims. (Cl. 200—145)

The invention relates to a three-phase A.C. power circuit-breaker, in which in three parallel planes lie three current loops with substantially parallel legs and each of these loops is provided with one or two arc-control devices—each incorporated in one of the parallel legs—with lateral gas outlets, each of said arc-control devices containing a stationary contact and cooperating with a longitudinally movable switching member. Various constructions of such circuit-breakers are known. A construction with two arc-control devices for each loop is described in "Schakelingen," No. 33, March 1942, p. 474. The so-called Conel circuit-breaker, illustrated in "Schakelingen," No. 58, July 1956, p. 23, forms a construction with one arc-control device for each loop.

The invention has arisen from experiments with circuit-breakers of the type mentioned, with two arc-control devices for each current loop, from which it appeared that upon interruption of the current no proper arc positioning is attained, i.e., that when an arc is drawn in the arc-control devices and when gas under pressure consequently develops in said arc-control devices, the arc is unsteady and does not take up the proper position in front of the gas outlet. This phenomenon limits the circuit-breaking capacity of the circuit-breaker.

The invention meets this difficulty to a considerable degree and moreover opens various favourable new possibilities.

It is characterized in that in the central loop the gas outlet of each arc-control device lies in the plane through the two legs of this loop; that in each of the two outer loops the gas outlet of each arc-control device diverges relative to the gas outlet of the corresponding arc-control device of the central loop to a value α , determined by the formula

$$\alpha = \alpha_0 \left(\frac{a}{b} \right)^n$$

in which α_0 has a value of about 25° , n is about 2.8, a is the distance between the two legs of each of the loops, and b is the distance between the planes of adjacent loops; and that the ratio a/b is between about 0.75 and about 0.45.

As will be elucidated below, a striking improvement of the arc positioning is achieved with this construction, to the extent that during a first experiment with an arrangement with two arc-control devices for each current loop an approximate doubling of the circuit-breaking capacity was already possible.

With regard to a three-phase circuit-breaker of the type mentioned in the first paragraph of this specification it is known that the resultant of the forces which are exerted on any given leg, i.e. also on an arc drawn in that leg, by the currents in all the other legs, as a function of time may assume values greatly varying in direction and magnitude. Owing to this the arc positioning is greatly hampered ("Schakelingen," No. 58, p. 19).

FIGURE 1 is a view in section of 6 conductors which define the current loops of the three phases.

FIGURES 2 through 4 show one embodiment of the invention. FIGURE 2 is a vertical section, FIGURE 3 is a horizontal section along the line III—III of FIGURE

2

2 and FIGURE 4 is a diagrammatic plan on a smaller scale of the six arc-control devices.

The invention is based, among other things, on the realization that the ratio of the distance a between the two legs of each of the loops to the distance b between the planes of adjacent loops, i.e. the ratio a/b , is a quantity which in several respects is decisive for the properties of the circuit-breaker. This may be elucidated with reference to FIGURE 1, in which a diagrammatic cross-section is given of the six conductors which form the legs of the current loops of the three phases. On each of the legs forces are exerted by the currents in the other legs. It has been found that the greatest forces occur during the switching of highly asymmetric currents such as may occur for low values of $\cos \varphi$, a power factor. It has also been found that under these most unfavourable circumstances the main direction of the electrodynamic forces acting on each of the arcs, for the central loop lies in the plane through the two legs of this loop, while that for the two outer loops is determined by the formula

$$\alpha = \alpha_0 \left(\frac{a}{b} \right)^n \quad (I)$$

in which α is the angle indicated in FIGURE 1 between the said main direction and the plane of the loop in question, α_0 is a factor of about 25° , and n is an exponent with a value of about 2.8. By the main direction is to be understood the direction in which the greatest electrodynamic force occurs. Now according to the invention, in order that the arc positioning may become as favourable as possible for all the phases, these realizations are taken into account in positioning the gas outlets in the arc-control devices of the different phases in the way formulated above by making the centre lines of the various gas outlets to coincide everywhere with the said main direction.

This is done, also according to the invention, over a range of the ratio a/b extending from about 0.75 to about 0.45. The reason of this will appear later.

It has also been found that with the two outer loops it is possible to point out for each leg an angular range β , also shown in FIGURE 1, located symmetrically relative to the main direction α , within which range under varying circumstances the resultant of the electrodynamic forces may vary as regards its direction, and that the magnitude of this angle is determined by the formula

$$\beta = \beta_0 \left(\frac{a}{b} \right)^n \quad (II)$$

in which β_0 has a value of about 40° , while a , b and n have the same meaning as mentioned above.

It is seen that Formula II is of the same kind as Formula I. This means that as the ratio a/b is reduced to distinctly below the value 1, not only the angle α but also the range β of the direction of the resultant becomes more than proportionately smaller, a fact which is actually bound to promote an optimum arc positioning under any circumstances.

Further it has been found that with the central loop it is possible to point out for each leg an angular range γ , likewise located symmetrically relative to the main direction, within which range the resultant of the forces may fluctuate, and that the magnitude of this range γ is approximately twice that of the range β ; in this case the main direction of the electrodynamic force lies in the plane through the two legs of the central loop. From this it follows that for this loop, too, the arc positioning is greatly improved by a reduction of the ratio a/b .

The realization embodied in the Formula II for β makes it possible to choose the actual angular width δ of the gas outlets of the arc-control devices, viewed from the centre line of the arc-control device in question, in

the right way. For the two outer phases this angular width δ may be chosen at least equal to β , and for the central phase at least equal to γ . In this way it is ensured that during the switching the arc does not come into contact with the edges of the gas outlet, or at least as little as possible, a feature which greatly prolongs the life of the arc-control devices. On the other hand the dimensions of the outlets are partly also conditioned by the requirement of obtaining the gas pressure and velocity necessary for the arc extinction. From this point of view, 10, too, a reduction of the ratio a/b is favourable. It results in a more than proportionate reduction of the required minimum angular width of the gas outlet and thus provides for ample play for the adaptation of the gas outlet openings to the required gas pressure.

As stated above, the invention covers a range of the ratio a/b extending from about 0.75 to about 0.45. In fact, if this ratio is distinctly greater than 0.75, and if it is, for instance, nearly 1 or more than 1, which is the case with the above mentioned known circuit-breaker of the "Schakelingen," No. 33, March 1942, publication with two arc-control devices for each loop, then—as has now been found—the value of β determined by Formula II (and thus certainly that of γ as well) is already so great that it is no longer possible at all to develop in the arc-control devices a gas pressure and velocity sufficient for the extinction of the arc. In that case therefore it is senseless to follow the said formula.

If on the other hand the ratio a/b were made distinctly smaller than 0.45, a case would present itself which is already known for one control device for each current loop from the Conel circuit-breaker referred to above in the "Schakelingen," No. 58, July 1956, publication, and in which the angle α determined by Formula I becomes so small (at most a few degrees) that it is not necessary at all to design the two outer current loops differently from the central one as regards the direction of their gas outlets.

By means of the invention, however, a striking increase of the circuit-breaking capacity is achieved in the aforementioned range of a/b between about 0.75 and about 0.45, both when two arc-control devices for each loop are used and when one arc-control device for each loop is used.

The section of FIGURE 2 lies in the plane of one of the three phases. The two other phases lie behind the plane of the drawing.

The current loops of three phases are arranged in parallel planes in a vessel 1 filled with an insulating medium, such as oil. Each loop comprises a contact bridge 2 with two parallel contact rods 3, which cooperate with two stationary contacts 4. Each of these stationary contacts 4 is located in an arc-control device 5, made, e.g., of nylon, containing insulating bodies 15 and 16, with a lateral gas outlet 6. Both the stationary contact 4 and the arc-control device 5 are supported by a lead-in insulator 7 passing through the cover 8 of the vessel 1.

The contact bridges 2 of the three loops are coupled with and operated by a joint member 9, which extends perpendicular to the plane of the drawing in the vessel 1 and in a way not shown can be moved down with a view to opening the circuit-breaker and up with a view to closing the circuit-breaker. FIGURE 2 shows the circuit-breaker at a moment it is in course of being opened. Between each contact rod 3 and each stationary contact 4 an arc 10 is then drawn. In the arc-control device 5 gas under high pressure develops in the known way, which gas escapes through the gas outlet 6.

The two arc-control devices 5 in FIGURE 2 are placed

so close together that they are in contact with each other, in order to obtain a small ratio a/b . In the diagrammatic plan of FIGURE 4 the distances a and b are given; their ratio is less than 0.75.

The two arc-control devices of the central loop have gas outlets which are directed away from each other in the plane through the two legs of this loop. The two arc-control devices of each of the two outer loops have gas outlets each of which diverges over the angle α relative to the gas outlet of the corresponding arc-control device of the central loop. As appears from FIGURE 3, the actual angular width δ of the gas outlets is at least β for the two outer phases and at least γ for the central phase (which cannot be seen). In the case of a successfully applied value of the ratio a/b of about 0.6 the divergence α is about 7.5° and the angle β is about 10°.

The invention of course also applies to a double arc-control device, in which the two individual devices are combined to one single constructional unit.

What we claims is:

1. A three-phase A.C. electric circuit-breaker in which in three parallel planes lie three current loops with substantially parallel legs and each of these loops is provided with at least one arc-control device—each incorporated in one of the parallel legs—with lateral gas outlets, each of said arc-control devices containing a stationary contact and cooperating with a longitudinally movable switching member, characterized in that in the central loop and gas outlet of each arc-control device lies 25 in the plane through the two legs of said loop; that in each of the two outer loops the gas outlet of each arc-control device diverges relative to the gas outlet of the corresponding arc-control device of the central loop to a value α , determined by the formula

$$\alpha = \alpha_0 \left(\frac{a}{b} \right)^n$$

in which α_0 has a value of 25°, n is 2.8, a is the distance between the two legs of each of the loops, and b is the distance between the planes of adjacent loops; and that the ratio a/b is in the range between 0.75 and 0.45.

2. Apparatus according to claim 1, characterized in that each of the gas outlets of the two outer loops, viewed from the centre line of the arc-control device in question, 30 has an angular range of at least β , determined by the formula

$$\beta = \beta_0 \left(\frac{a}{b} \right)^n$$

in which β_0 has a value of 40°.

3. An apparatus according to claim 2, characterized in that each of the gas outlets of the central loop, viewed from the centre line of the arc-control device in question, has an angular range of at least γ , approximately equal to twice β .

4. An apparatus according to claim 1, characterized in that the ratio a/b is 0.6 and the divergence α 7.5°, while the angular width δ of the gas outlets of the arc-control devices for the outer loops exceeds an angle β of 10°, and for the central loop an angle γ of 20°.

5. An apparatus according to claim 1, with two arc-control devices for each loop, characterized in that the two arc-control devices of each loop are placed so close together that they are in contact with each other.
